UNITED STATES PATENT OFFICE.

PETER R. McLAFFERTY, OF NEW CASTLE, PENNSYLVANIA.

TOY.

1,295,779.

Specification of Letters Patent.

Patented Feb. 25, 1919.

Application filed May 4, 1918. Serial No. 232,613.

To all whom it may concern:

Be it known that I, PETER R. McLAFFERTY, a citizen of the United States, residing at New Castle, in the county of Lawrence and 5 State of Pennsylvania, have invented new and useful Improvements in Toys, of which the following is a specification.

This invention relates to a balancing toy and has for its primary object to construct a 10 toy in a manner that the figure thereof may have a plurality of movements and may assume a plurality of positions.

An object of the invention is to provide a toy in which the figure may be balanced in 15 a vertical position or in a horizontal position or any position intermediate of the two mentioned positions.

Another object of the invention is to provide a toy whereby upon slight adjustment 20 of a portion of the figure, the same will readily assume any angular position with relation to a support.

With these and other objects in view the invention will be better understood from the 25 following detailed description taken in connection with the accompanying drawing wherein:

Figure 1 is a perspective view of a toy constructed in accordance with my invention.

Fig. 2 is an enlarged view of the arm showing its connection with the body.

Figs. 3 and 4 are diagrammatic views showing two positions of the figure.

Fig. 5 is a detailed view of a slight modification of my invention.

My invention in one of its forms consists of a figure 1 the feet 2 of which are curved in predetermined directions as clearly shown 40 in Figs. 3 and 4 so as to readily rock upon the top surface 3 of a stand 4. Surrounding the surface 3 is an upstanding flange 5 which will prevent movement of the figure off of the surface 3 when violently rocked, although

45 I wish it to be understood that it is not absolutely necessary to have the flange 5 or in

fact the stand 4 as the figure may be rocked upon any other suitable surface.

The arms 6 of the figure are pivotally connected to the body in any suitable manner such as by screws 7 which may be tightened to a degree great enough to allow the arm to assume any angular position. If found advantageous in practice the screw may have a thumb piece 8 as clearly shown in Fig. 5 so 55 that an operator may readily tighten the screw should the connection between the arm and the body become loose. Fixed to the arms is a downwardly curved pole 9 to the extremities of which are connected weights 60 10. This pole curves in the proper direction to place the center of gravity below the figure.

From the foregoing description it will be seen that by slightly adjusting the arms 6 65 the center of gravity may be readily changed to allow the figure to assume any angular direction while at the same time the figure may be oscillated in any of its angular positions. Of course it is to be understood that 70 the device may be constructed in various other manners than that shown for accomplishing an adjustable connection between the weights and the body and therefore I do not desire to be limited except as set forth in 75 the claim hereto appended.

Having described my invention, what I claim is:

In combination with a stand having a flat top and an upstanding retaining flange enclosing the top, a figure having curved feet adapted to move rockingly upon the top of the stand within the upstanding flange, said figure being further provided with arms adjustably connected to the body, a pole fixed 85 to the arms and weights carried by the pole, said flange preventing falling of the figure from the stand during creeping movement caused by its rocking.

In testimony whereof I affix my signature. 90

PETER R. McLAFFERTY.
